(57) **CLAIM**

What is claimed is the ornamental design for a decorative palm tree for cats, as shown and described.

DESCRIPTION

FIG. 1 is a perspective view of a decorative palm tree for cats, showing the new design;

FIG. 2 is a reduced top plan view thereof; and

FIG. 3 is a reduced bottom plan view thereof.

FIG. 4 is a reduced left-side elevational view thereof, the right-side elevational view being a mirror image thereof;

FIG. 5 is a reduced rear elevational view thereof;

FIG. 6 is a reduced front elevational view thereof; and,

FIG. 7 is a reduced perspective view thereof, showing the shelves in an alternate, rotated position.
